UNITED STATES PATENT OFFICE.

WALTER E. DUNCANSON, OF NEW YORK, N. Y., ASSIGNOR TO THE J. G. WILSON CORPORATION, OF NEW YORK, N. Y., A CORPORATION OF VIRGINIA.

AUTOMATIC FIRE SHUTTER.

Application filed February 7, 1925. Serial No. 7,513.

This invention relates to automatic fire resisting screens or shutters of the type in which the screen is arranged to be coiled up on and uncoiled from a rotary roller 5 and is normally maintained in coiled up condition within a protecting housing. In shutters of this type the shutter is automatically released and caused to uncoil from the roller to close the opening adjacent to 10 which it is installed upon the occurrence of a dangerous rise in temperature.

It is highly desirable in fire shutters of this type that the controlling and actuating mechanism therefor, shall be so constructed 15 that the shutter may be tripped manually to cause the shutter to descend and close the opening and thereafter may be again coiled up on the roller in testing the operation of the shutter. Shutters of this type 20 have heretofore been constructed so that they may be tripped manually. In coiling up the shutter after testing the same, it is desirable that after setting the shutter holding mechanism the operator should be able 25 to raise the shutter part way while standing on the floor of the building and then, to complete the raising of the shutter while standing on the sill of the window or on any other suitable elevated support. This 30 makes it highly important that some means shall be provided for holding the shutter in any partially raised position during the manual raising operation.

One of the objects of the present invention 35 is to improve the construction and mode of operation of coiling fire shutters of the type above described and to provide such shutters with new and improved operating and controlling mechanisms which will hold 40 the shutter normally in open position in a reliable manner, which may be readily released automatically upon the occurrence of a dangerous rise of temperature or manually 45 for the purpose of testing the operation and which will hold the shutter effectively in partially raised position during the manual raising of the same.

In certain shutters of this type heretofore 50 constructed the shutter acquires a great deal of momentum during its descent. The result is that considerable force is required to stop the shutter when it reaches a closed position and this results in heavy strains on the parts and in the production of a large

amount of noise and vibration. To avoid 55 this undesirable result shutters of this type have been provided with means for retarding the downward movement of the shutter. The means heretofore devised however, for this purpose, has been such as to retard also 60 the upward movement of the shutter and this greatly increases the labor required and the difficulties involved in coiling up the shutter.

Another object of the present invention is 65 to provide a coiling fire shutter with novel and improved means for retarding the closing movement of the shutter which will have no retarding effect upon the opening movement of the shutter.

With these and other objects in view the invention involves certain novel and improved features, constructions and combinations of parts hereinafter described and particularly pointed out in the claims, the 70 advantages of which will be readily understood and appreciated by those skilled in the art.

The invention will be clearly understood 75 from the accompanying drawings illustrating the invention in its preferred form and the following detailed description of the constructions therein shown.

In the drawings—

Fig. 1 is a view in vertical section of a 80 shutter embodying the invention, this view being taken substantially on the line 1—1 of Fig. 2;

Fig. 2 is a view in side elevation with 85 certain parts broken away of the mechanism shown in Fig. 1, looking from the left in said figure;

Fig. 3 is a view similar to Fig. 1 taken 90 substantially on the line 3—3 of Fig. 2, and showing certain of the parts in different positions from the positions in which they are shown in Fig. 1;

Fig. 4 is a view similar to Fig. 3 of a 95 portion of the mechanism shown in said figure showing certain of the parts in different positions;

Fig. 5 is a sectional view taken substantially on the line 5—5 of Fig. 3 and illustrating the structure at one end of the roller; 100

Fig. 6 is a view in horizontal section taken substantially on the line 6—6 of Fig. 1.

The coiling shutter embodied in the pre-

ent construction may be of any suitable or well known type such as that made up of jointed metallic slats and is illustrated diagrammatically in Figs. 1, 3 and 4. This shutter is indicated at 2 in the drawings and is mounted adjacent an opening 4 in a wall 6 of a building to close this opening in case of fire. The shutter 2 is mounted at its ends upon shafts one of which indicated at 8, is rotatably mounted in a suitable bearing in the shutter frame. This shaft carries a barrel 9 fixed thereto and carrying annular supports 10 upon which the shutter is coiled, the inner margin of 15 the shutter being secured to these supports.

The outer margin of the shutter comprises plates 12 attached to one of the slats and carrying at their lower ends an angle bar 14. The ends of the shutter slide in 20 channels in channel bars 16 located at the opposite sides of the door opening.

The barrel 9 is acted upon by coiled springs (not shown) which partially counterbalance the weight of the shutter. When 25 the shaft is released, however, the weight of the shutter will cause the shutter, when open, to move toward closed position against the tension of the springs. In order to increase the force tending to close the shutter during 30 the first part of the closing movement thereof, a weight bar 18 is mounted with its ends engaging in guides in channel bars 20 to slide vertically in a direction parallel with the shutter, the channel bars 20 being located 35 at opposite sides of the door opening, as shown in Figure 6. The angle bar 14 on the lower end of the shutter projects across the path of movement of the weight bar 18, so that the weight bar is adapted to act upon 40 the shutter during a part of the movement thereof. When the shutter is completely open, the weight bar rests upon the angle bar 14, as shown in Figure 1, and is supported thereby. Thus, when the shutter is 45 released, the shutter will be acted upon by its own overbalancing weight and also by the weight of the bar 18.

If the bar 18 continues to act on the shutter until the shutter reaches closed position, 50 the shutter will end its movement with a violent impact or stop, which is, of course, undesirable. Furthermore, the bar 18, if acting on the shutter when the shutter is closed, will make it particularly difficult for 55 anyone who is trapped in a building by the closing of the shutter, to raise the shutter manually and escape. To avoid these results, the movement of the bar 18 with the shutter is arrested before the shutter reaches closed 60 position by means of a pair of bolts 22 extending across the respective channel bars 20. The engagement of the ends of the bar with these bolts stops the movement of the bar and the shutter continues its movement 65 to closed position.

The shutter is held in fully opened position by means of shutter latches which engage the ends of the angle bar 14. These latches are indicated at 24 and are mounted to slide in tubular guides 26, each secured to 70 a member attached to a rock shaft 28, the latches being acted upon by coiled springs 30 which tend to advance the same into operating position. The latches are each provided with inclined faces 32 arranged to be 75 engaged by the bar 18 and the angle bar 14 to cause the retraction of the latches as the shutter is raised. The rock shaft 28 is mounted in bearings in supports 34 attached to the frame of the shutter mechanism and to one end of the shaft is secured an arm 36 to which is attached the mechanism for holding the latch normally in operating position. This mechanism comprises chains 38 and 40 which are connected by a fusible link 42. The chain 40 passes about guide pulleys 44 and through the tubular element 48 mounted in the wall 6 and extending from the exterior to the interior of the building. On the interior of the building the chain passes about a guide pulley 50 and is attached at its end to a hook 52. Thus the chain 40 is attached at a fixed point remote from the shutter latches within the building, where it may be conveniently released in testing the 95 operation of the shutter mechanism.

Figure 3 of the drawings shows the positions of the parts as the shutter is being raised, just before the bar 18 engages the latches, and Figure 1 shows in full lines, the 100 positions of the parts when the shutter is in fully open position. Figure 1 shows in dot and dash lines and Figure 4 shows in full lines, the position of the parts just after the latches are released.

The latches 24 of course, will hold the shutter only in fully opened position. In order to hold the shutter in partly opened position while it is being raised manually, a latch mechanism is provided which acts on the shaft 8. To this end the disk 53 at one end of the shaft is provided with a series of radially projecting teeth 54 which are arranged to be engaged by a pawl 56 pivoted on a lever 60. The lever 60 is pivoted at 110 61 on the frame of the shutter mechanism and when the latches are located in operating position the lever 60 is held in operating position as shown in Figure 3, except when the shutter is fully opened. The lever 60 is held in this position by means of a chain 62 attached at one end to the arm 36 and passing about a pulley 64 and a coiled spring 66 connecting the chain 62 with the outer end of the lever 60. The pawl 56 is free to turn on the lever 60 as the pawl is engaged by the teeth 54 during the raising of the shutter so that the pawl does not obstruct the rotation of the shaft 8. The turning movement of the pawl in the opposite direction, 120 125 130

however, is limited by means of a pin 68 secured in the lever 60, so that the pawl will prevent the rotation of the shaft 8 in a direction to cause the lowering of the shutter.

5 When the shutter approaches its completely opened position, the lever 60 is engaged by a pin 70 secured to the plate 12 which swings the lever out of operating position as shown in Figures 1 and 4. Thus the lever 60 and pawl 56 will act to prevent the downward movement of the shutter while it is being opened manually until the shutter is adjacent its fully opened position. The lever 60 and pawl 56 are then thrown out of operation by the upward movement of the shutter and the shutter is held in fully opened position only by the action of the latches 24.

When the link 42 fuses or the chain 40 is released from the hook 52 the arm 36 is released and the arms 26 with the latches 24 swing downwardly to the position shown in dot and dash lines in Figure 1 and in full lines in Figure 4, under the weight of the shutter and the bar 18. This slackens the chain 62 and relieves the tension on the spring 66 so that the lever 60 and the pawl 56 remain in the positions shown in Figures 1 and 4, until the shutter is again raised, the lever 60 being somewhat overbalanced on its outer arm. The lever 60 is swung back to the position shown in Figure 3 when the latches 24 are reset in the position shown in this figure by the pull exerted upon the chain 62 and the spring 66, the spring 66 then yieldingly holding the lever in position.

In order to retard the downward movement of the shutter so that the shutter will not come to the end of its movement with great violence, an escapement mechanism is provided to act on the shaft 8 as the shutter descends. This escapement mechanism comprises a ratchet wheel 72 mounted to turn loosely on the shaft 8 and to be rotated with the shaft during the downward movement of the shutter by means of a pawl 74 pivoted on the disk 53 and arranged to engage the teeth of the ratchet wheel. This connection between the disk and the ratchet wheel enables the disk and shaft 8 to turn freely without rotating the ratchet wheel as the shutter is raised. The rotation of the ratchet wheel 72 with the shaft 8 during the downward movement of the shutter is retarded by mechanism comprising pawls 76 and 78 secured rigidly together and pivoted upon a stud 80 mounted in the frame of the shutter mechanism. To the pawls 76 and 78 is secured a depending arm 82 arranged to swing across the axis of the shaft 8 and having a weight 84 adjustably secured to the lower end thereof. This arm is provided at an intermediate point therein with an elongated opening 86 in which the shaft 8 is engaged.

65 As the ratchet wheel 72 is rotated in a

clockwise direction, Figure 4, during the downward movement of the shutter, the rotation of the wheel is retarded, first by one of the pawls 76 and 78 and then by the other pawl, the pawls being oscillated about the stud 80 during this operation. The oscillation of the pawls swings the arm 82 back and forth across the axis of the shaft 8, the weight 84 retarding the swinging movement of the arm away from the axis of said shaft in either direction and thereby retarding the rotation of the ratchet wheel. The extent of the retarding action of the weight 84 on the wheel may be adjusted by adjusting the weight longitudinally of the arm 82.

This retarding mechanism will have no retarding effect upon the movement of the shutter as the shutter is raised but will allow the shutter to move with perfect freedom at this time. Figure 3 shows the positions of the parts of the retarding mechanism as the shutter is being raised, the pawl 74 clicking over the teeth of the ratchet wheel 72 as the disk 53 is rotated.

In resetting the shutter mechanism after the link 42 is fused the chain 40 is preferably released from the hook 52 to enable a new link readily to be inserted between the chain 40 and the chain 38. The mechanism may then be reset by restoring the chain 40 to the hook 52. In resetting the mechanism after testing it is only necessary to replace the chain 40 on said hook. In either case, the resetting operation swings the arm 36 downwardly into the position shown in full lines in Figures 1 and 3 and swings the arms 26 and the latches 24 upwardly into the positions shown in full lines in these figures. As the arm 36 is swung downwardly into the position shown in these figures, the pull on the chain 62 will restore the lever 60 to operating position, as shown in Figure 3. Thus, this lever will be in position to prevent the downward movement of the shutter while the shutter is being raised manually. When the shutter is completely raised, however, this lever will be swung out of operating position into the position shown in Figures 1 and 4 as stated above.

As the shutter is raised, the angle iron 14 will pick up the weight bar from the bolts 22 as the iron reaches said bar and as the shutter continues its upward movement, the bar 18 engages the inclined faces 32 of the latches 24 and forces back the latches in the guideways in arms 26 until the bar and angle iron have passed the latches. The latches will then spring forwardly into operating position as shown in Figure 1.

As shown in Figures 1 and 3, one of the side flanges on each of the channel members 16 is bent laterally as indicated at 88, over the upper end of the adjacent channel member 20 in which the weight 18 slides. This

will prevent the weight 18 from being removed from the guides 20 by lifting the weight out of the upper ends of the guides. The weight 18 is made of sufficient width 5 and is arranged to fit sufficiently close at its ends to the adjacent walls of the channel members 20 to prevent one end of the weight from being lifted above the other end of the weight into a position such that the weight 10 may be removed laterally from the channel members.

It is to be noted that in the present construction the guides 20 for the ends of the weight bar 18 are located outside of the 15 channel bars 16 in which the lateral edges of the shutter engage.

The latches 24 constitute shutter latches acting on the shutter as distinguished from the latches acting on the roller upon which 20 the shutter is rolled, the latches 24 acting to hold the shutter in its fully raised position. The lever 60, together with the pawl 56 constitute a roller latch acting on the devices upon which the shutter is rolled to hold the 25 shutter in partially raised position, this latch being thrown out of operation when the shutter is fully raised. By the co-operative action of these latches, the shutter will be held in fully raised position so that it may 30 be released, either manually to test the same, or upon the occurrence of an abnormal rise in temperature and will be held in partially raised position while it is being raised manually.

35 It is to be understood that the invention is not limited to the particular construction and arrangement of parts of the illustrated embodiment of the invention but that the invention may be embodied in other forms 40 within the scope of the claims.

Having explained the nature and object of the invention and having specifically described a mechanism embodying the invention in its preferred form, what is claimed 45 is—

1. An automatic fire shutter mechanism having in combination a movable shutter constructed and arranged for movement across a wall opening, a shutter latch for 50 engaging the shutter to latch the same in open position, and means for holding the latch in shutter latching position comprising a fusible element arranged to be operated manually to release the shutter and to be 55 operated automatically to release the shutter by the fusing of said element.

2. An automatic fire shutter mechanism having in combination a movable shutter constructed and arranged for movement 60 across a wall opening, a pivoted shutter latch for engaging beneath the shutter when fully raised to latch the same in open position, and means for holding the latch in shutter latching position comprising a fusible element arranged to be operated manually to

release the shutter and to be operated automatically to release the shutter by the fusing of said element.

3. An automatic fire shutter mechanism having in combination a movable shutter constructed and arranged for movement across a wall opening, means inoperative when the shutter is fully raised for holding the shutter from descending when partially raised, and independent means inoperative when the shutter is partially raised 75 for holding the shutter in fully raised position.

4. An automatic fire shutter mechanism having in combination, a flexible shutter constructed and arranged for movement across a wall opening, a roller on which the shutter may be coiled and from which it may be uncoiled to open and close the opening, 80 a roller latch for holding the shutter from dropping when partially raised, a latch for engaging the shutter to hold the shutter in 85 fully raised position, and means for rendering both latches inoperative to allow the shutter to descend.

5. An automatic fire shutter mechanism having in combination a flexible shutter constructed and arranged for movement across a wall opening, a roller on which the shutter may be coiled and from which it may be uncoiled to open and close the opening, 95 a roller latch for holding the shutter from dropping when partially raised, a latch for engaging the shutter to hold the shutter in fully raised position, means for throwing 100 out the first latch when the shutter is fully raised, and fusible means for releasing the second latch upon the occurrence of a dangerous rise in temperature.

6. An automatic fire shutter mechanism having in combination a flexible shutter constructed and arranged for movement across a wall opening, a roller on which the shutter may be coiled and from which it may be uncoiled to open and close the opening, 110 a roller latch for holding the shutter from dropping when partially raised, a latch for engaging the shutter to hold the shutter in 115 fully raised position, means for throwing out the first latch when the shutter is fully raised, fusible means for releasing the second latch upon the occurrence of a dangerous rise in temperature, and common means for resetting both latches.

7. An automatic fire shutter mechanism having in combination a flexible shutter constructed and arranged for movement across a wall opening, a roller on which the shutter may be coiled and from which it may be uncoiled to open and close the opening, 125 a roller latch for holding the shutter from dropping when partially raised, a latch for engaging the shutter to hold the shutter in fully raised position, means for throwing 130 out the first latch when the shutter is fully

raised, and fusible means for releasing the second latch upon the occurrence of a dangerous rise in temperature, and for causing the continued release of the first latch as the 5 shutter falls.

8. An automatic fire shutter mechanism having in combination a flexible shutter constructed and arranged for movement across a wall opening, a roller on which the shutter may be coiled and from which it may be uncoiled to open and close the opening, a roller latch for holding the shutter from dropping when partially raised, a latch for engaging the shutter to hold the shutter in 10 fully raised position, means for throwing out the first latch when the shutter is fully raised, fusible means for releasing the second latch upon the occurrence of a dangerous rise in temperature, and for causing the continued release of the first latch as the shutter falls, and common means for resetting both of said latches.

9. An automatic fire shutter mechanism having in combination a movable shutter 25 constructed and arranged for movement across a wall opening, means for holding the shutter normally in open position comprising an element fusible upon the occurrence of a dangerous rise in temperature, and independent means unaffected by the upward movement of the shutter arranged to retard the downward movement of the shutter whenever said holding means is released.

10. An automatic fire shutter mechanism 30 having in combination a movable shutter constructed and arranged for movement across a wall opening, means for holding the shutter normally in open position comprising an element fusible upon the occurrence of a dangerous rise in temperature, and independent means arranged to retard the downward movement of the shutter whenever said holding means is released and furnishing substantially no resistance to the 45 lifting of the shutter.

11. An automatic fire shutter mechanism having in combination a movable shutter constructed and arranged for movement across a wall opening, means for holding the shutter normally in open position comprising an element fusible upon the occurrence of a dangerous rise in temperature, independent means arranged to retard the downward movement of the shutter whenever the 50 shutter is released, and a ratchet mechanism connecting the shutter with said retarding means whereby the retarding means will be set in operation upon each release of the shutter and will be ineffective when the 55 shutter is raised.

12. An automatic fire shutter mechanism 60 having in combination a flexible shutter constructed and arranged for movement across a wall opening, a roller upon which the shutter may be coiled up and from which

it may be uncoiled, a device mounted to rotate loosely about the axis of the shutter roller, a retarding mechanism arranged to act on the same, a second device secured to the shutter roller to rotate therewith, a latch 70 for engaging the latter device to hold the same from rotation in one direction, a ratchet connecting said devices to cause the former to rotate with the latter when the shutter descends, said ratchet allowing the 75 former device to remain stationary when the shutter is raised.

13. An automatic fire shutter mechanism having in combination a movable shutter constructed and arranged for movement 80 across a wall opening, latching means for holding the shutter in fully opened position, latching means for holding the shutter in partially opened position, and means for throwing out the latter latching means when 85 the shutter is fully opened.

14. An automatic fire shutter mechanism having in combination a movable shutter constructed and arranged for movement 90 across a wall opening, latching means for holding the shutter in fully opened position, latching means for holding the shutter in partially opened position, and means for throwing out the latter latching means when 95 the shutter is fully opened and for maintaining it out of operation when the shutter is released.

15. An automatic fire shutter mechanism having in combination a flexible shutter constructed and arranged for movement across a 100 wall opening, a roller on which the shutter may be coiled and from which it may be uncoiled, to open and close said opening, shutter latching means for latching the shutter while the roller is unlatched, and roller latching means for latching the roller while 105 the shutter is unlatched.

16. An automatic fire shutter mechanism having in combination a movable shutter constructed and arranged for movement 110 across a wall opening, a holding device for holding the shutter against downward movement and means operated by the upward movement of the shutter for releasing said holding device.

17. An automatic fire shutter mechanism having in combination a movable shutter constructed and arranged for movement across a wall opening, rotatable devices upon which the shutter may be rolled, a member rotatable with relation to said devices, means for connecting said member for rotation with said devices during each downward movement of the shutter, arranged to allow said devices to rotate independently of said member during the raising of the shutter and means for holding said member from movement while connected with said devices to maintain the shutter in raised position.

18. An automatic fire shutter mechanism having in combination a movable shutter constructed and arranged for movement across a wall opening, rotary devices upon which the shutter may be rolled, a retarding device for retarding the downward movement of the shutter, comprising a swinging arm, pawls rigidly connected with said arm, a toothed wheel arranged to be engaged by the pawls and means for connecting the wheel for rotation with said devices during the downward movement of the shutter and to allow said devices to rotate independently of the wheel during the upward movement of the shutter.
19. An automatic fire shutter mechanism having in combination a movable shutter constructed and arranged for movement across a wall opening, rotatable devices upon which the shutter may be rolled, a retarding mechanism for retarding the downward movement of the shutter, comprising a swinging arm, pawls mounted on said arm, a toothed wheel arranged to be engaged by said pawls, means for connecting said wheel for rotation with said devices and a weight adjustably mounted on said arm.
20. An automatic fire shutter mechanism having in combination a movable shutter constructed and arranged for movement across a wall opening, rotatable devices upon which the shutter may be rolled and retarding devices for retarding the downward movement of the shutter, means by which the retarding devices may be adjusted to increase or diminish the retarding action thereof.
21. An automatic fire shutter mechanism having in combination a movable shutter constructed and arranged for movement across a wall opening, rotatable devices upon which the shutter may be rolled, a retarding mechanism for retarding the downward movement of the shutter comprising a swinging arm, pawls mounted on said arm, a toothed wheel arranged to be engaged by said pawls, means for connecting said wheel for rotation with said devices, and means independent of said arm for holding the shutter in raised position.
22. An automatic fire shutter mechanism having in combination a movable shutter constructed and arranged for movement across a wall opening, rotatable devices upon which the shutter may be rolled, a member rotatable with relation to said devices, means for connecting said member for rotation with said devices during the downward movement of the shutter, arranged to allow said devices to rotate independently of said member during the raising of the shutter and means for holding said member from movement while connected with said devices to maintain the shutter in raised position comprising a device fusible upon the occurrence of a dangerous rise in temperature.
23. An automatic fire shutter mechanism having in combination a movable shutter constructed and arranged for movement across a wall opening, means for holding the shutter normally in open position arranged to be actuated to release the shutter upon the occurrence of a dangerous rise in temperature, and independent means for retarding the downward movement of the shutter whenever said holding means is released.
24. An automatic fire shutter mechanism having in combination a movable shutter constructed and arranged for movement across a wall opening, means for retarding the downward movement of the shutter, comprising an oscillatory weighted arm, means moving with the shutter as the shutter descends for oscillating said arm, and means independent of said arm for holding the shutter from descending.
25. An automatic fire shutter mechanism having in combination a movable shutter constructed and arranged for movement across a wall opening, retarding mechanism for retarding intermittently the downward movement of the shutter, and means independent of said retarding mechanism for holding the shutter from descending.

Signed at New York, this 6th day of February, 1925.

WALTER E. DUNCANSON.
